[57] CLAIM

The ornamental design for a combined window ventilator and rain catcher, as shown.

DESCRIPTION

FIG. 1 is a front perspective view of a combined window ventilator and rain catcher showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a rear perspective view thereof inserted between a window and a window sill shown in phantom for illustrative purposes only, and forms no part of the claimed design.
